Primary Examiner — Marianne Pandozzi

(57) **CLAIM**

The ornamental design for set of interchangeable beverage containers, as shown and described.

DESCRIPTION

FIG. 1 is a perspective view of a set of interchangeable beverage containers showing my new design;

FIG. 2 is an exploded perspective view showing only one container consisting of a chamber, a seal, a cap, and an identification button of the set of interchangeable beverage containers, the rest removed for ease of illustration;

FIG. 3 is a front elevational view showing a $\frac{1}{6}^{\text{th}}$ size volume container with the rest of the set of interchangeable beverage containers removed for ease of illustration;

FIG. 4 is a top plan view thereof;

FIG. 5 is a bottom plan view thereof;

FIG. 6 is a perspective view showing a $\frac{1}{8}^{\text{th}}$ size volume container with the rest of the set of interchangeable beverage containers removed for ease of illustration;

FIG. 7 is a perspective view showing a $\frac{1}{6}^{\text{th}}$ size volume container with the rest of the set of interchangeable beverage containers removed for ease of illustration;

FIG. 8 is a perspective view showing a $\frac{1}{4}^{\text{th}}$ size volume container with the rest of the set of interchangeable beverage containers removed for ease of illustration;

FIG. 9 is a perspective view showing a $\frac{1}{3}^{\text{rd}}$ size volume container with the rest of the set of interchangeable beverage containers removed for ease of illustration;

FIG. 10 is a perspective view showing a $\frac{1}{2}$ size volume container with the rest of the set of interchangeable beverage containers removed for ease of illustration;

FIG. 11 is a top plan view of FIG. 6;

FIG. 12 is a bottom plan view thereof;

FIG. 13 is a top plan view of FIG. 8;

FIG. 14 is a bottom plan view of FIG. 8;

FIG. 15 is a top plan view of FIG. 9;

FIG. 16 bottom plan view of FIG. 9;

FIG. 17 is a top plan view of FIG. 10; and,

FIG. 18 bottom plan view of FIG. 10.
